UNITED STATES PATENT OFFICE.

JOHN D. BUCKLEY AND EDWARD H. PHINNEY, OF BRUNSWICK, MAINE,
ASSIGNORS, BY DIRECT AND MESNE ASSIGNMENTS, OF PART INTER-
EST TO JOHN D. BUCKLEY, JOHN W. CHASE, AND GEORGE L. CHASE,
OF BRUNSWICK, MAINE.

TROLLEY-POLE BASE.

SPECIFICATION forming part of Letters Patent No. 691,236, dated January 14, 1902.

Application filed April 22, 1901. Serial No. 56,965. (No model.)

To all whom it may concern:

Be it known that we, JOHN D. BUCKLEY and EDWARD H. PHINNEY, citizens of the United States, residing at Brunswick, in the county 5 of Cumberland and State of Maine, have invented certain new and useful Improvements in Trolley-Pole Bases; and we do declare the following to be a full, clear, and exact description of the invention, such as will enable 10 others skilled in the art to which it appertains to make and use the same.

The invention relates to trolley-pole bases.

The object of the invention is to provide a device of this character which shall be simple of construction, durable in use, comparatively inexpensive of production, and efficient in action.

With this and other objects in view the invention consists of certain novel features of 20 construction, combination, and arrangement of parts, which will be hereinafter more fully described, and particularly pointed out in the appended claims.

In the accompanying drawings, Figure 1 is 25 a vertical sectional view of our improved trolley-pole base, a portion of the trolley-pole being shown in place. Fig. 2 is a similar view taken at right angles to Fig. 1. Fig. 3 is a detail perspective view of one of the springs.

Referring to the drawings, 1 denotes the 30 base-plate of our improved trolley-pole base, provided with binding-screws 2 for the connection therewith of the conductor-wires and formed with an annular vertical flange 3, provided with an annular groove 4 on its outer face.

5 denotes a cap-plate having a downwardly-projecting annular flange 6 surrounding the 35 annular flange 3 and provided with an annular groove 7, which coacts with the groove 4 to form a ball-race for the reception of anti-friction-balls 8, which may be let into said race through an aperture 9, closed by a screw-threaded plug 10, and when in place will prevent the separation of the cap-plate from 40 the base, while permitting of a free rotary movement of the cap with respect to the base-plate.

11 denotes a hood bolted or otherwise secured to the base-plate and provided with a 50 stop and with a longitudinal opening 12.

13 denotes a ball-socket consisting of a sleeve 14, located within said base and journaled upon a bolt 15, and provided with an extension 16 to receive the lower end of the 55 trolley-pole 17.

18 denotes two coiled springs, each located within the hood about the sleeve 14 and each having one end secured to the extension 13 and its other end secured to the hood. The 60 energy of this spring is exerted to hold the extension 13 and its ball 17 in a vertical position.

19 denotes a spring secured within the casting and having its free end projecting from the path of movement of the trolley-pole, so 65 that should the trolley-pole slip the wire it will strike said spring and prevent damage to the hood and other parts of the device. In other words, this spring acts as a buffer to check the movement of trolley-poles which 70 accidentally slip the wires.

From the foregoing description, taken in connection with the accompanying drawings, the construction, mode of operation, and advantages of our invention will be readily understood without requiring a more extended explanation.

Various changes in the form, proportion, and details of construction may be made 80 within the scope of the invention without departing from the spirit or sacrificing any of the advantages thereof.

Having thus described our invention, what we claim, and desire to secure by Letters Patent, is—

1. In a trolley-pole base, the combination with the base-plate having an annular flange provided with an annular groove, of a cap-plate provided with an annular downwardly-projecting flange having an annular groove 90 coacting with the first-named groove to form a race, balls located in said race and locking the base-plate and cap-plate against displacement, a hood secured to the cap-plate and provided with a longitudinal slot, and a 95 spring-actuated pole-socket consisting of a

horizontally-disposed sleeve journaled in said hood and having an extension projecting through said slot, substantially as set forth.

2. In a trolley-pole base, the combination

5 with the base-plate having an annular flange provided with an annular groove, of a cap-plate provided with an annular downwardly-projecting flange having an annular groove coacting with the first-named groove to form

10 a race, balls located in said race and locking the base-plate and cap-plate against displacement, a hood secured to the cap-plate and provided with a longitudinal slot, a spring-actuated pole-socket consisting of a horizon-

tally-disposed sleeve journaled in said hood 15 and having an extension projecting through said slot, and a buffer-spring located in the path of movement of the vertical extension to serve as a buffer for the same.

In testimony whereof we have hereunto set 20 our hands in presence of two subscribing witnesses.

JOHN D. BUCKLEY.
E. H. PHINNEY.
